ABSTRACT: A septum-changing inlet apparatus for chromatographs having a ported body and a septum strip moved linearly in successive increments relative to the port of said body to overlie said port with unused or imperforated parts of the septum strip. A septum compression plate movable between a position pressing the septum strip, overlying the port of the body against the face of the inlet and a septum release position. Fluid pressure actuated means is adapted to move said plate and as said plate is actuated or moved, the septum strip is moved linearly.

INVENTOR

BY AGENT.

AUTOMATIC SEPTUM-CHANGING MECHANISM

CROSS-REFERENCES TO RELATED APPLICATIONS

Tom H. Vannus, Automatic Septum Changing Inlet, filed July 28, 1969, Ser. No. 845,433, now U.S. Pat. No. 3,566,697.

John D. Reid, Chromatograph Inlet with Rotating Septum filed Dec. 18, 1969, Ser. No. 886,142.

BACKGROUND OF THE INVENTION

1. Field of the Invention

This invention relates generally to inlets for chromatographs and relates more particularly to chromatograph inlets having a septum that can be automatically moved to bring various parts thereof into operative position.

2. Description of the Prior Art

Conventional inlets for chromatographs have various problems, disadvantages and operating difficulties. As is well known, septums retain their sealing reliability for from six to 10 injections and then must be replaced. When such septums are replaced, the chromatograph instrument must be shut down and there is, of course, an interruption of carrier gas flow and a loss of carrier gas while the used septum is removed from the inlet and a new septum installed. There is a waiting period while the instrument regains its operating temperature after a shutdown. There is also always the danger that the operator will have his fingers burned while changing the septum.

My previous instrument, disclosed in my copending application Ser. No. 845,433 provides a septum changer wherein a septum disc is carried by a rotatably mounted ratchet wheel having a plurality of annularly spaced outer ports which are successively moved into alignment with a port of the body of the chromatograph, there being means for successively rotating the ratchet wheel to move said outer ports respectively into alignment with the port in the body.

The John D. Reid instrument, disclosed in his copending application filed Dec. 18, 1969, Ser. No. 886,142, comprises a body for connection with a chromatograph column. There is a circular septum which is rotated by a motor, the motor being operated for a predetermined period of time to successively rotate the septum predetermined increments to bring unused parts of the septum into alignment with a column adaptor.

SUMMARY OF THE INVENTION

The present invention moves a strip of septum material linearly or longitudinally an increment at a time to replace a part of the septum material that has been perforated several times by a syringe needle with a part of the material that has not been used.

Means is provided for pressing against the adjacent part of a chromatograph inlet having the inlet opening for a needle that portion of the septum material to be used to provide a proper seal with said inlet. After this part of the septum strip has been perforated a number of times so that it no longer seals reliably the pressure on the part of the septum strip aligned with the inlet port of the chromatograph inlet is relieved and the strip moved an increment to bring an unused part into alignment with said inlet port. When the septum strip has been thus moved, the pressure is again applied to provide a secure seal with the chromatograph inlet.

OBJECTS AND ADVANTAGES OF THE INVENTION

It is an object of the invention to provide a simple and effective automatic septum-changing mechanism.

Another object of the invention is to provide mechanism of this character wherein a strip of septum material is moved linearly or longitudinally. Such a strip may be of considerable length so that a great many changes may be made because of the length of septum strips possible.

The characteristics and advantages of the invention are further sufficiently referred to in connection with the follow-

ing detailed description of the accompanying drawings which represent one embodiment. After considering this example, skilled persons will understand that many variations may be made without departing from the principles disclosed, and I contemplate the employment of any structures, arrangements or modes of operation that are properly within the scope of the appended claims.

BRIEF DESCRIPTION OF THE DRAWINGS

10 Referring to the drawings, which are for illustrative purposes only:

FIG. 1 is a schematic side elevational view of mechanism embodying the invention and partial section;

15 FIG. 2 is a top plan view thereof; and

FIG. 3 is a partially exploded perspective view of the mechanism.

DESCRIPTION OF THE PREFERRED EMBODIMENT

20 Referring more particularly to the drawing, there is a chromatograph inlet 10 which may be of the standard type, said inlet having an entrance part 12.

25 At the forward end of the inlet entrance 12 is a septum supporting and feeding assembly indicated generally at 14, said assembly comprising a frame indicated generally at 15 including a frame member 16 having an upstanding septum compressor plate 18. There is a guide 20 carried by the frame 15. Plate 18 has a bore 23 which aligns with the inlet port 12. A knurled shaft 24 is located in frame 15 extending through the

30 top portion of frame 14 on which a ratchet wheel 54 is mounted. Spaced forwardly from shaft 24 is an idler roller 26. The idler roller is mounted on a shaft 28 having both ends fixed to the frame of the assembly 14. The spacing between the knurled shaft 24 and the idler roller 26 is such as to operably receive the septum strip 22.

35 Sufficient pressure is exerted on the septum by the knurled shaft to effect lineal movement of the septum strip with rotation of said knurled shaft 24, said idler roller 26 serving as a backup for the septum strip so that said strip will be positively moved linearly upon rotation of the knurled shaft 24.

40 The frame of the septum supporting and feeding assembly has a pair of ears 32 which are spaced apart and have aligned openings therein for pivot pin 30 which is rotatably mounted in a support means not shown. Pivot pin 30 is secured in said aligned openings.

45 Assembly 14 is pivoted on pin 30 so that the septum supporting and feeding assembly may be swung toward and away from the entrance 12 of the inlet 10.

50 Means for actuating assembly 14 comprises a fluid pressure cylinder 36 having an ear 38 at one end and pivotally attached to an ear 40 by means of a pivot pin 42, said ear 40 being secured to a support 44. Cylinder 36 has a piston, not shown, attached to a piston rod 46 extending from the opposite end from said cylinder 36 and pivotally connected at 48 to the free end of lever 32. It is to be understood that piston rod 46 passes through an opening provided therefor in the adjacent end of cylinder 36 and packing means is provided to provide a seal for said piston rod 46. The cylinder and piston rod arrangement is well known. Cylinder 36 is provided with conduits 50 and 52 at respective ends for operating fluid under pressure.

55 There is means, not shown, for controlling the supply of pressure fluid to the conduits 50 and 52 and for venting the respective ends of the cylinder 36 whereby the piston is actuated longitudinally in the cylinder 36.

60 Means for rotating the knurled shaft 24 is provided and includes a ratchet wheel 54 secured to one end of said knurled shaft. A pair of pawls 56 and 58 are disposed tangentially relative to the ratchet 54, said pawls being mounted at their forward ends as shown in FIGS. 1 and 2 on pivot pins 60 and 62 which are parallel to each other and which are operably attached to a bracket 64 attached to a fixed mounting not shown. Spring 70 has its ends secured in openings provided therefore in the respective pawls 56 and 58, said spring 75 yieldingly urging the pawls toward each other.

Pawl 56 has a hook-shaped free end 72 adapted to engage the teeth 74 of the ratchet wheel and pawl 58 has a pointed free end 76 also adapted to engage the teeth 74 of the ratchet wheel.

When a portion of the septum strip 22 is being used, fluid pressure is supplied to the cylinder 36 by way of the conduit 52, the conduit 50 then being vented to atmosphere so that the piston urges the lever 32 upwardly causing the septum compressor plate 18 to press the septum tightly against the adjacent end of the inlet entrance 12. The needle of a sample-carrying syringe is inserted into the port 23 provided therefore in the plate 18, said port being in alignment with the inlet opening orifice of the inlet 10 so that said needle when forced through the septum 22, will enter said inlet opening. Sample material discharged from the syringe is thereby delivered into the inlet 10 and handled in the usual manner by the chromatograph.

When the septum strip is to be moved to position, a fresh part of the septum strip into operable relationship with the inlet, the cylinder 36 is provided with pressure fluid by way of the conduit 50, the conduit 52 then being vented to atmosphere so that the piston will move the lever 32 in counterclockwise direction, as shown in FIG. 3, and cause the frame of the septum carrying and feeding mechanism to move away from the entrance 12 of the inlet. As the frame is thus moved, the hook 72 of the pawl 56 causes the ratchet wheel to move in a clockwise direction, as shown in FIG. 2, while at the same time, the point 76 of the pawl 58 slips over the adjacent tooth and engages said adjacent tooth. This clockwise movement of the ratchet wheel causes the septum strip to be moved linearly a limited increment. Fluid is then supplied to cylinder 36 to cause the piston to move upwardly and actuate lever 32 in the counterclockwise direction. As the frame of the septum supporting and actuating mechanism is thus caused to move towards the inlet entrance 12, the ratchet wheel 54 is further moved in the clockwise direction to further move the septum strip which is then sealingly pressed against the entrance 12 in the inlet. With the clockwise movement of the ratchet wheel effected by pawl 58, the hooked end 72 of pawl 56 slips over the adjacent leading tooth of the ratchet wheel. The movements of the ratchet wheel effected by pawls 56 and 58 when the septum carrying and feeding assembly is moved away from and then toward the inlet, effects sufficient movement of the septum strip 22 to bring into alignment with the port 23 and the inlet opening of the chromatograph inlet 10 an imperforated or unused part of the septum strip.

The septum strip may be of any suitable character. As shown, the septum strip comprises a plurality of layers of septum material which may include a relatively soft central layer and somewhat harder layers at each side of the central layer, the layers being molded or otherwise suitably secured together.

The invention and its attendant advantages will be un-

derstood from the foregoing description and it will be apparent that various changes may be made in the form, construction and arrangement of the parts of the invention without departing from the spirit and scope thereof or sacrificing its material advantages, the product or article hereinbefore described being merely by way of example, and I do not wish to be restricted to the specific form shown or uses mentioned except as defined in the accompanying claims.

I claim:

1. Automatic septum-changing mechanism, comprising:
A. Septum carrying and feeding assembly including:
a. a frame with a septum compression plate having a needle-receiving opening therethrough:
b. means for moving said frame and its compression plate between a forward position and a rearward position, a septum strip being adapted to be operable disposed at the forward side of the compression plate,
c. and means for moving a septum strip linearly at the forward side of the compression plate when the compression plate is moved away from its forward position.
2. The invention defined by claim 1 wherein the means for moving a septum strip linearly comprises a rotatably mounted knurled shaft engageable with said septum strip, said shaft being rotated when the compression plate is moved from its forward position.
3. The invention defined by claim 2 wherein there is backup means adjacent the knurled shaft and spaced forwardly therefrom.
4. The invention defined by claim 3, wherein the septum carrying and feeding assembly is pivotally mounted for movement between its forward position and a rearward position.
5. The invention defined by claim 3, including guide means adjacent carried by the frame from the knurled shaft for guiding a septum strip across said compression plate.
6. The invention defined by claim 4, wherein the means for moving the frame and compression plate between the forward and rearward positions comprises a fluid pressure operated actuator.
7. The invention defined by claim 2, including means for operably rotating said knurled shaft to advance a septum strip as the compression plate moves from its forward position to its rearward position and also operable rotates such knurled shaft in the same direction as said plate is moved from its rearward to its forward position.
8. The invention defined by claim 7 wherein said means for rotating said knurled shaft comprises a ratchet wheel secured to said knurled shaft and a pair of pawls oppositely engaging said ratchet wheel, one of said pawls effecting rotation of said knurled shaft in one direction when the compression plate is moved rearwardly while the other pawl effects rotation of said knurled shaft in the same direction when said compression plate is moved forwardly.
